(57) **CLAIM**

The ornamental design for a mobile head mounted display, as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a front, top and left side perspective view of a first embodiment of a mobile head mounted display.

FIG. 2 is a rear, top and right side perspective view thereof.

FIG. 3 is a front elevation view thereof.

FIG. 4 is a rear side elevation view thereof.

FIG. 5 is a right side elevation view thereof, with the left side elevation view being identical to the right side elevation view.

FIG. 6 is a top plan view thereof; and,

FIG. 7 is a bottom plan view thereof.

The broken lines shown in the drawings are for illustrative purposes only and form no part of the claimed design.
